US00D795420S

(12) **United States Design Patent** (10) **Patent No.:** **US D795,420 S**
Rimsa et al. (45) **Date of Patent:** **** Aug. 22, 2017**

(54) **TISSUE TRANSFER APPARATUS**

(71) Applicant: **LifeCell Corporation**, Branchburg, NJ (US)

(72) Inventors: **Joseph Rimsa**, Palo Alto, CA (US); **Brian J. Domecus**, San Francisco, CA (US)

(73) Assignee: **LifeCell Corporation**, Branchburg, NJ (US)

(**) Term: **15 Years**

(21) Appl. No.: **29/557,749**

(22) Filed: **Mar. 11, 2016**

Related U.S. Application Data

(63) Continuation of application No. 29/533,766, filed on Jul. 22, 2015, now Pat. No. Des. 751,692, which is a continuation of application No. 29/497,697, filed on Jul. 28, 2014, now Pat. No. Des. 737,431, which is a continuation of application No. 29/435,991, filed on Oct. 31, 2012, now Pat. No. Des. 710,003, which is a continuation-in-part of application No. 13/371,270, filed on Feb. 10, 2012, now Pat. No. 9,314,568.

(60) Provisional application No. 61/510,967, filed on Jul. 22, 2011, provisional application No. 61/489,811, filed on May 25, 2011, provisional application No. 61/442,060, filed on Feb. 11, 2011.

CLAIM

The ornamental design for a tissue transfer apparatus, as shown and described.

DESCRIPTION

FIG. 1 is a perspective view of a tissue transfer apparatus; FIG. 2 is a perspective view thereof; FIG. 3 is a reverse detailed perspective thereof; FIG. 4 is a side view thereof; FIG. 5 is a top view thereof; FIG. 6 is a bottom view thereof; FIG. 7 is a front end view thereof; FIG. 8 is a back end view thereof; FIG. 9 is a right side view thereof; and, FIG. 10 is a left side view thereof.
All features illustrated in phantom line are expressly disclaimed and form no part of the claimed design.

1 Claim, 8 Drawing Sheets
